Attorney

UNITED STATES PATENT OFFICE.

FRANK W. GAULT, JR., OF LOUISVILLE, KENTUCKY, ASSIGNOR OF ONE-HALF TO
H. J. GREIVE, OF LOUISVILLE, KENTUCKY.

GAS BURNER.

Application filed November 9, 1925. Serial No. 67,902.

This invention relates to an improvement in gas burners for furnaces, melting pots, and the like.

An object of this invention is to provide the shell carrying the burner nozzle with a number of rings for increasing the height of the shell for the purpose of directing the flame and products of combustion in close proximity to the article being heated. The burners are employed in heating various shaped articles and are generally attached to a manifold so that a great number of burners may be used and arranged about the surface of the receptacle to be heated and thereby subject the contents of the receptacle to an intense heat from a number of different points. Some of these receptacles, fire boxes or melting pots, have concave or similarly shaped bottoms, and where the shells are all of the same height, only the lowermost portion of such receptacles receive an intense heat, and while the side walls receive heat it is not as intense as it is at the lowermost portion of the receptacle. To overcome this objection this invention provides a number of rings on the shell of each burner, whereby the rings may be adjusted with respect to the shell and the surface of the receptacle, that the same intense heat will be transmitted to the receptacle from each burner.

Another object of the invention is to provide a burner nozzle supported within the burner shell and adapted to be adjusted vertically therein. In some instances, the adjustment of the burner nozzle is sufficient to meet the requirements and the rings may not be dispensed with, or by the use of the rings and adjustment of the nozzle a more intense heat may be obtained.

The invention consists of certain novel features of construction and combination of parts which will be hereinafter described and pointed out in the claims:

In the accompanying drawings:

Figure 1 is a vertical sectional view showing the parts assembled;

Figure 2 is a perspective view of the invention showing the shell and rings with another form of burner arranged prior to assembling; and

Figure 3 is a top plan view of a similar nozzle to that shown in Figure 1.

A tubular burner shell 10 is provided with a base having a central screw-threaded open-

ing 11 to which a supply pipe may be attached for the delivery of gas or gasoline.

Mounted within the shell 10 is a cup-shaped nozzle 12 having openings or holes 14, 14 in the bottom thereof through which the gas enters. The upper portion of the nozzle flares or projects outwardly over the upper end of the shell 10, and is preferably curved on its lower surface 13 conforming to the flaring upper end of the shell, which limits the downward movement of the nozzle within the shell. The nozzle 12 is capable of adjustment within the shell 10, and is held at different elevations by a set screw 14', to regulate the size of the gas chamber in the shell and to move the burner to and from the object to be heated.

Mounted upon the exterior of the shell 10 is a ring 15 adapted to be held at various elevations on the shell by a set-screw 16, and movably mounted on the ring 15 is another ring 17 held in adjusted position thereon by a set-screw 18. The rings 15 and 17 are interfitted or telescopic and both may be lowered or raised upon the shell 10 to the elevation demanded for the purpose of bringing the flame and heat in juxtaposition to the receptacle.

The lower ring 15 is provided with a slot 19 for the reception of the set screw 14, and permits of the ring being moved vertically on the shell 10.

It has been found that a shell made of a height to accomplish this result soon deteriorates due to the intense heat to which it is subjected. This produces an expensive shell because of the necessity of replacing the same, but by providing the rings 15 and 17 and nozzle 12 of a suitable heat resisting metal they may be replaced more readily and cheaper, when they become fused or burnt, than can be accomplished by substituting a new shell under the same conditions. Furthermore, with the rings they may be adjusted to different elevations, whereas if shells were provided, it would be necessary to have a great number of shells of different heights. This contingency is provided for in the rings which may be of uniform or different sizes and adjusted to their respective shell to meet the requirements at a much smaller cost.

In Figure 2 another nozzle 20 is provided which may be screwed into the opening 11

of the shell 10 and adjusted therein to suit the requirements and is held therein by a set screw 21. The upper end of the nozzle 20 is closed and provided with a series of slots 22 and 23 radiating from a central opening 24. The slots 22 are preferably of a smaller diameter than the slots 23.

In Figure 3 is shown the nozzle 12 provided with slots 25 instead of the holes 14.

10 Claims:

1. A gas burner, comprising a shell having a fuel inlet opening therein, a burner nozzle fitted within the shell and capable of vertical adjustment therein, means for holding the nozzle in its adjusted position, and telescopic rings mounted on the shell for increasing the height of the shell, and means

for holding the rings in adjusted relation to each other.

2. A gas burner, comprising a shell having a fuel inlet opening therein, a cup shaped nozzle having a sliding fit within the shell, said nozzle having the bottom thereof extending across said shell and forming a control of the fuel admitted to the shell, said bottom being provided with a plurality of openings for the admission of fuel to the cup-shaped nozzle where it is ignited, and means for adjustably supporting the nozzle within the shell for regulating the position of the nozzle with respect to the object being heated and the supply of fuel to the shell.
